UNITED STATES PATENT OFFICE.

RICHARD SELIGMANN, OF SEATTLE, WASHINGTON.

BUTTON.

1,230,804.

Specification of Letters Patent. Patented June 19, 1917.

Application filed January 26, 1917. Serial No. 144,778.

To all whom it may concern:

Be it known that I, RICHARD SELIGMANN, a citizen of the United States, and resident of Seattle, in the county of King and State 5 of Washington, have invented certain new and useful Improvements in Buttons, of which the following is a specification.

This invention relates to buttons of the so-called lever head type, and has for its object to provide a button of this class adapted to be used as a collar button or for any other use for which it may be adapted, the same being provided with a post having a member pivotally mounted thereon and a head pivotally connected to said member, whereby 10 both the head and member may be swung up in line with the post when desired to facilitate its being passed through the button-hole.

15 A further object of the invention is to provide means whereby the head may be locked to the post when in contracted position.

With these and other objects in view, the invention consists of certain novel features 20 of construction, as will be more fully described, and particularly pointed out in the appended claims.

In the accompanying drawings:

Figure 1—is a side elevation partly in section of a button having my improved type 25 of extendible head.

Fig. 2—is a sectional side elevation showing the head portion of the button in extended position.

30 Fig. 3—is a perspective view showing the hinge plate which is adapted to be pivotally connected to the button post.

Fig. 4—is a perspective view of the back plate of the button head showing the joint end which is hinged to the hinge plate; also 40 showing the spring opening adapted to be passed over the ball end of the post to lock the head in closed position.

Fig. 5—is a view showing the end of the 45 post to which the hinge plate is pivotally connected.

Referring to the drawings, 10 designates the post of the button which is preferably drawn up into tubular form, from a flat 50 plate 11 onto which plate is preferably rolled the usual gold front 12, thereby forming the fixed head of the button. The opposite end of this post has its sides pressed inwardly as at 13, see Fig. 5, forming a flat 55 portion which is pierced at 14, and through which the hinge pintle 15 is passed. The

outer end of this post is shown as being provided with a ball 15 which provides a lock for the swinging head, presently described.

The primary object of this invention is to 60 provide a head on the button which instead of being fixed rigidly to the post as is the case with some buttons, may be extended in line with the post, whereby it is adapted to be more readily passed through the button-holes of starched goods such as cuffs, collars and the like, and also to be used in soft cuffs when desired. To accomplish this result in a simple and effective manner, I have provided a hinge plate 17 having a joint eye 26 65 at one end through which the pivot pin 15 passes to hinge this plate to the end of the post 10. The free end of this plate is provided with another hinge eye member 18 and to this hinge eye member is connected the 70 backing plate 19 of the swinging head 20. One end of this backing plate is provided with extending portions folded over to provide a pair of eyes 21 which straddles the eye 18 in the hinge plate and through both 75 of which is passed a pivot pin 22.

In order to secure this back plate to the post when not in folded position, I have punched a hole 23 in this plate and have raised the stock around the edge of the hole 80 and have also split this stock at the points 24 so that when the plate is swung at right angles to the axis of the post the ball 16 may be forced through this opening 23 and the resilient lips of the stock around the opening will grip the ball and securely bind the plate thereto.

Any style of ornamented front plate 25 may be attached to this back plate 19 and I have shown them connected by rolling the 95 edges of one over those of the other.

A button of my improved construction has many advantages over the usual lever type of button among others being; First, when the head is extended in line with the post as 100 illustrated in Fig. 2, it may be readily passed through the button-holes of a stiffly starched collar or cuff and that without enlarging the button-holes which is not the case where a large ball or bean end is used 105 or when a head of the flat rigid type is employed; second, a button of my improved type may have both heads large enough to absolutely prevent any possibility of being drawn through the unstarched button-holes 110 of a soft cuff; third, the extendible head may serve the purpose of a lever to draw to-

gether the ends of a collar, upon being passed through the button-holes thereof.

It is found in practice that the ordinary lever button head in being turned up in line with the post that a portion of the head lies back against the side of the post, thereby requiring additional length of post to operate it, but by the use of my improved construction of button head, no part of the head is folded back upon the side of the post, therefore the length of the post may be reduced to the minimum.

Another feature of this invention is the provision of a spring 27 fixed at one end to the plate 17 by a screw 28 or other means; and its free end is adapted to enter a notch 29 in the hinge portion of the head when this head is in extended position so as to yieldably retain the same in extended position to facilitate its being passed through the button-holes.

I have illustrated one means of carrying out my invention but I do not wish to limit myself to this specific construction as various changes in the hinging of the parts, in the locking mechanism and also in the shape and form of the several features, may be necessary. I, therefore, desire it to be understood that I reserve the privilege of resorting to all mechanical changes to which the device is susceptible, the invention being defined by the appended claims.

Copies of this patent may be obtained for five cents each, by addressing the "Commissioner of Patents, Washington, D. C."

I claim:

1. A button comprising a post, a member hinged to said post, and a head hinged to said member whereby said head and member may be extended in line with the post.

2. A button comprising a post, a member hinged to said post, a head hinged to said member whereby said head and member may be extended in line with the post, and means for locking said head to the post when in contracted position.

3. A button comprising a post, a plate connected to swing on said post, a button head connected to swing on said plate, whereby both may be extended in line with the post, a ball on said post, said head being provided with an opening adapted to spring over said ball to lock the head and post together.

4. A button comprising a post, a member hinged to said post, a head hinged to said member whereby said head and member may be extended in line with the post, means for yieldably extending said head in extended position, and means for locking said head to the post when in folded position.

In testimony whereof I affix my signature in presence of a witness.

RICHARD SELIGMANN.
